FORREST E. CARDULLO, OF CINCINNATI, OHIO, ASSIGNOR TO THE G. A. GRAY COMPANY, OF CINCINNATI, OHIO, A CORPORATION OF OHIO.

DRIVING-GEAR FOR METAL-PLANERS.

1,384,382.

Specification of Letters Patent. Patented July 12, 1921.

Application filed April 15, 1921. Serial No. 461,538.

To all whom it may concern:

Be it known that I, FORREST E. CARDULLO, a citizen of the United States, residing at Cincinnati, in the county of Hamilton and 5 State of Ohio, have invented new and useful Improvements in Driving-Gears for Metal-Planers, of which the following is a specification.

My invention relates to improvements in 10 metal planers and particularly to driving gear for same.

Metal planers are provided with reduction gearing transmitting power from a pulley or motor shaft which usually runs at a speed 15 of from 250 or less to 1,000 or more revolutions per minute, to a work table which runs at a speed of approximately 20 feet or less to 120 feet or more per minute. The purpose of this gearing is to reduce the speed and in- 20 crease the driving force applied to the work table.

It is customary to employ for this purpose spur gears, which are objectionable from the fact that when they are imperfectly cut 25 or somewhat worn they give an irregular motion to the table which causes so called chatter marks on the work. Helical or herringbone gears which give great smoothness of action, may be employed, but helical 30 gears produce heavy end thrusts in the shafting, and side thrusts against the table, while herringbone gearing requires a great deal of room and the gears and racks are difficult and expensive to manufacture and 35 to attach.

The cutting tools employed in planing metal not only oppose the motion of the work and table, but also tend to thrust or push the work in the direction in which the 40 tools are fed. This last mentioned force is commonly called side thrust. Since the tools are usually fed away from the operating side of the machine (commonly called the right hand side) this pushes the table 45 against the left hand faces of the ways, and creates an objectionable tendency to lift the table.

Furthermore, since it is customary and desirable to place the work close to the operating side of the table, and since the driving rack is usually placed at the center of the table, the cutting force and the driving force do not usually occur in the same vertical plane, but during the greater part of 50 the time occur in such a way as to produce

a torque tending to rotate the table in a clockwise direction when viewed from above, crowding the forward part of the table against the left hand faces of the ways and the rear part of the table against the 60 right hand faces of the ways, thus creating additional friction and wear.

My invention employs helical gears so designed as to balance the end thrusts resulting from the use of this type of gears, and 65 secures a very compact arrangement of the driving gears, equalizing the wear on the gear teeth, balancing in great measure the side thrust of the cutting tool and the torque caused by the action of the cutting tool. 70

My invention is illustrated in the accompanying drawings, in which:-

Figure 1 is a perspective of a metal planer, 75 part of the driving gears being shown in dotted lines, the action of the cutting tool being shown, and part of the bed cut away;

Fig. 2 is a plan view of the gearing of a planer and attendant parts, with all superimposed parts removed;

Fig. 3 is a plan view of an alternative 80 form of such gearing;

Fig. 4 is a partial axial section through the bull gears;

Fig. 5 is an elevation of the bull gear;

Fig. 6 is a plan view of the bull pinion; 85

Fig. 7 is an axial section and side elevation of the split collar by which the intermediate gear is fixed to the bull pinion;

Fig. 8 is a partial section of the second intermediate gear which is fixed to the bull 90 pinion by the split collar;

Fig. 9 is a partial section of the intermediate pinion;

Fig. 10 is a partial section of the first intermediate gear fixed on the intermediate 95 pinion; and

Fig. 11 is a partial section of the pulley or motor shaft pinion.

Referring now to the drawings (exclusive of Fig. 3), A is the housing, B the rail with tool holders b and tool b¹, bed C with ways c, c¹, and work table D with V's d, d¹, adapted to reciprocate in said ways c, c¹ respectively. The work W is clamped to the work table in the usual way. All the gears are 105 helical.

The work table has on its under side helical cut racks of equal pitch and opposite angle, d², d³ the former on the right or work side of the table being wider than the one 110

on the left side. Meshing with these racks d^2 , d^3 , are two gears e , e^1 , respectively, cut upon co-axial cylindrical surfaces of a unitary member E commonly called the bull gear, rotatably on the shaft e^2 . The gear e is a right hand helix and gear e^1 is a left hand helix, and the angle of helix is preferably about 23° .

Left hand gear f and right hand gear f^1 cut upon co-axial cylindrical surfaces of a unitary member F commonly called the bull pinion, rotatable on the shaft f^2 , mesh with the bull gears e , e^1 respectively. Keyed to the member F between the gears f and f^1 is the split collar f^4 , f^5 , and to this collar is bolted a gear f^3 of left hand helix commonly called the second intermediate gear, preferably with its angle of helix about 10° .

Meshing with the gear f^3 is the right hand helical pinion g , commonly called the intermediate pinion, rotatively secured to the right hand helical gear g^1 , commonly called the first intermediate gear, fixed to the shaft g^2 .

The gear g^1 meshes with the left hand helical pinion h commonly called the pulley shaft pinion, fixed to the driving shaft h^1 which is rotated in the usual manner first in one direction and then in the other to reciprocate the work table for the cutting and return strokes alternately. All these shafts, e^2 , f^2 , g^3 and h^1 are journaled in the bed C of the planer. Shaft g^2 is provided with a thrust bearing g^3 and shaft h^1 with a thrust bearing h^2 to insure against endwise movement.

The work table D resting on its V's d , d^1 , in the ways c , c^1 respectively, may be moved by the gearing only in a direction at right angles to the several shafts, and the gears e and e^1 meshing with the racks d^2 , d^3 respectively, and the pinions f , f^1 meshing with the gears e , e^1 respectively, are therefore held in alinement and restrained against sidewise movement, that is in a direction parallel to their axes, except for such slight movement as is caused by the back lash of the gearing.

When the pulley shaft h^1 revolves in a counter-clockwise direction as indicated by the arrow in Fig. 2, gears g^1 and g revolve in a clockwise direction, gears f^3 , f and f^1 revolve in a counter-clockwise direction and gears e and e^1 revolve in a clockwise direction, driving the racks d^2 , d^3 and the work table D toward the rear end of the planer, that is, in the direction for the cutting stroke.

Pinion h , being left hand, tends to pull gear g^1 toward the working side of the planer but is unable to do so because of the thrust bearing g^3 . Pinion g , being right hand, tends to pull gear f^3 toward the working side or right hand of the planer, and in doing so reduces the load carried by pinion f^1 and increases the load carried by pinion f

since the end thrust of pinion f exerted upon gear e must be greater than the end thrust exerted upon gear e^1 by pinion f^1 by the amount of end thrust exerted upon pinion g by gear f^3 . The ratios of the gear diameters and the helical angles of the gear are preferably made such that the end thrust of pinion f^1 is about $3\frac{1}{2}$ times, and that of pinion f about $4\frac{1}{2}$ times, that of pinion g . As a result of this difference, the load carried by pinion f^1 , gear e^1 and rack d^3 is less than that carried by pinion f , gear e and rack d^2 in the proportion indicated.

I, therefore, make pinion f , gear e and rack d^2 wider than pinion f^1 , gear e^1 and rack d^3 as before described, so that the load per inch of face carried by each is the same and so that the wear occurring upon each set of gears will be the same. The wider rack is placed under the working side of the table, so that the greater driving force is applied to that side of the table on which the work is usually placed, thus reducing the tendency of the cutting force to rotate the table upon a horizontal plane.

During the cutting stroke, the action of the gearing is such as to tend to draw the table toward the working side of the machine. However, it is usual to employ the cutting tool b^1 in such a way that it feeds away from the working side of the machine as the work progresses. Under these conditions the side pressure of the tool tends to push the work and the work table to which it is fastened away from the working side of the machine. The tendency of the gearing to thrust the table toward the working side of the machine therefore serves only to counteract in part the tendency of the tool to thrust the table away from this side. Obviously exact balancing of these side thrusts is not possible under all conditions, because working conditions and needs vary the side thrust caused by the working tool upon the work.

With the alternative form of my invention shown in Fig. 3, the racks d^2 , d^3 are closer together than when the form shown in Fig. 2 is used. Meshing with these racks are two bull gears e^3 , e^4 , respectively. Gears f^4 and f^5 mesh with the gears e^3 , e^4 respectively. In this form of the device f^3 need not be of the special construction shown in Fig. 2, but a unitary gear fixed to the shaft F.

In all other respects the alternative construction is the same as the form shown in Fig. 2.

I claim as my invention and desire to secure by Letters Patent of the United States:—

1. A drive for a metal planer, having in combination, a planer table having on its under side two helical cut racks of opposite angle, helical gearing for driving each of said racks, the angles of said gears so

- arranged that all unabsorbed end thrust will be so transmitted to the table as to tend to balance the normal side thrust of the cutting tool.
5. A drive for a metal planer, having in combination two helical cut racks on the work table and a train of helical cut gears from the source of power to said racks, said gears and racks adapted to substantially 10 balance all thrusts created by helical cutting, means for absorbing the side thrust in the power and intermediate shaft, and means for substantially balancing the side thrust resulting from the normal pressure 15 of the cutting tool on the work.
3. A drive for a metal planer, having in combination a planer table carrying on its under side a right and a left hand rack driven respectively by a left and right hand 20 helical gear, said gears driven respectively by a right and left hand helical pinion, to which is fixed a left hand helical gear driven by a right hand helical pinion, so arranged that the end thrust created by the said right 25 hand helical pinion is transmitted through the gearing to the table, tending to thrust it toward the working side of the machine.
4. A drive for a metal planer, having in combination, a planer table with two helical 30 cut racks of opposite angle, the width of each of said racks proportioned to the pressure thereon, helical gearing for driving each of said racks, the angles of said gears so arranged that all unabsorbed end thrust 35 will be so transmitted to the table as to tend to balance the normal side thrust of the cutting tool.
5. A drive for a metal planer, having in combination, a planer table with two helical 40 cut racks of opposite angle, helical gearing for driving each of said racks, the right hand cut rack gear and its rack being wider than the other, the angles of said gears so arranged that all unabsorbed end thrust
- will be so transmitted to the table as to tend to balance the normal side thrust of the cutting tool.
6. A drive for a metal planer, having in combination two helical cut racks on the work table of equal pitch and opposite angle, 50 the one on the work side of the table wider than the other; a bull gear with a face of suitable width, pitch and angle for each of said racks; a bull pinion with a face of suitable width, pitch and angle for each of 55 said bull gears; a second intermediate helical cut gear rotatable with the bull pinion and of lesser angle; an intermediate pinion of suitable width, pitch and angle to mesh with said second intermediate gear; a first 60 intermediate helical cut gear rotatable with said intermediate pinion; a drive pinion of suitable width, pitch and angle to mesh with said first intermediate gear; and thrust bearings for the drive shaft and first intermediate shafts.
7. In combination with a helical cut gear drive for metal planers, two racks on the work table, one toward each side, of equal pitch but opposite angle, the widths of said 70 racks being substantially proportional to the driving load carried by each.
8. In combination with a helical cut gear drive for metal planers, two racks on the work table, one toward each side, of equal pitch but opposite angle, the widths of said racks being substantially proportional to the driving load carried by each, the rack carrying the greater driving load being placed 75 under the work side of the table.
- In testimony whereof I have hereunto set my hand in presence of two subscribing witnesses.
